UNITED STATES PATENT OFFICE.

OTTO WUPPER AND ALBERT BECKER, OF GEVELSBERG, GERMANY.

BOTTLE-STOPPER.

SPECIFICATION forming part of Letters Patent No. 583,966, dated June 8, 1897.

Application filed October 7, 1895. Serial No. 564,958. (No model.) Patented in Germany December 17, 1894, No. 82,659; in France March 9, 1895, No. 245,687; in Belgium March 9, 1895, No. 114,503; in Austria April 10, 1895, No. 45/1,929; in Hungary April 10, 1895, No. 2,787, and in England April 11, 1895, No. 7,741.

To all whom it may concern:

Be it known that we, OTTO WUPPER and ALBERT BECKER, subjects of the Emperor of Germany, residing at Gevelsberg, Westphalia, Germany, have invented new and useful Improvements in Stoppering Bottles and the Like, (for which we have obtained a patent in Germany, No. 82,659, bearing date December 17, 1894; in France, No. 245,687, bearing date March 9, 1895, and No. 245,687, additional patent, bearing date March 25, 1895; in Belgium, No. 114,503, bearing date March 9, 1895, and No. 114,905, additional patent, bearing date April 2, 1895; in Austria, R. T. 45/1,929, bearing date April 10, 1895; in Hungary, No. 2,787, bearing date April 10, 1895, and in Great Britain, No. 7,741, bearing date April 11, 1895,) of which the following is a specification.

Our invention has for its object a new and useful device for closing bottles and the like hermetically-closed vessels which differs from such known for this purpose by the manner of fixing the device to the bottle or vessel. This is done in such a manner that the device cannot be taken off from the bottle and stolen. Furthermore, the device secures, by means of its practical construction, many advantages which in the ordinary constructions are not obtainable.

How we carry our invention into effect is shown on the accompanying drawings, of which—

Figure 1 shows the new device in a closed state; Fig. 2, opened. Figs. 3 and 4 are views seen from right and left side of Fig. 1, respectively. Figs. 5, 7, and 8 are details of construction. Fig. 6 is a modified construction of the fastening-ring. Figs. 9, 10, and 40 11 show a modified construction of the closing device. Fig. 12 is a special arrangement of the stopple.

Our new device consists of a fastening-ring A, which is formed of two halves a b, being linked together at one end by a bolt c. The free end of part a carries a bolt e, to which is linked a lever d, but so that the bolt is left a little free. According to this the free end of the half b is hook-shaped, in such a manner that the rectangular slot forming the hook stands a little back from the bolt e, as will

be understood from Fig. 7. In order to join the halves a b and form the complete fastening-ring A, they must therefore be pressed together, Fig. 8. Now to the link end of the ring are attached turnable bars i, which seize a rod f, the free end of which is hook-shaped, so as to take up the top end of a wire link k, which is connected with the lever d. The rod f is provided with a hooked end and carries the stopple h, of porcelain or other suitable material, having an oblong hole which prevents the turning of the stopple on the rod f.

The closing mechanism thus described may be attached to the bottle in the following manner: The halves a b of the fastening-ring are laid around the neck of the bottle and then hooked together. It cannot be taken off from the bottle without damaging the same, for the spring-like action which takes place by pressing a and b together does not allow the ring to open. To prevent its downstroke when the device is opened, the bottle may be provided with little projections, as is shown in dotted lines, Figs. 1 and 2, of which also the manner of using will be best understood.

The stopple is firmly pressed down upon the bottle by turning down the lever d and lifted from it when the lever is moved in the contrary direction, for which purpose it is provided with a convenient handle. The degree of opening the bottle may be thereby easily regulated, which is of great importance for waters; but in every other respect our new device has great advantages. It can be attached to the bottle without the help of an instrument, is not exposed to wear and tear, and does not require repairing. It may be also preferably used for conserve-boxes, in which case the device may be fitted with the fastening-ring illustrated in Fig. 6. Here both halves of the ring are connected by a vertically-arranged rivet, so that the ring opens in the horizontal plane. The joining together of the two halves is made, as before, by a corresponding rivet and a hook. For attaching the closing-pieces to the ring, flanges 7 are provided.

In Figs. 9 to 11 a modified construction of the device is shown. Instead of the solid rod f there is arranged a U-formed wire sledge m,

running through the stopple and being at its open ends connected to the fastening-ring A by a similar wire sledge *n*. The other end of *m* is bent a little downward, so as to form an ear, into which is caught the hook-shaped sledge *o* for the purpose as described before.

Fig. 12 illustrates a special construction of the stopple, which has for its object to isolate the india-rubber disk from the liquid in order to prevent the dirtying of the same, which always takes place when the disk is not often cleaned. For this purpose the stopple is provided with a screw *A'*, having a shoulder *R*, against which is screwed an ordinary cork *S*, so that a free space between the india-rubber disk *T* and the cork is gained. The latter, filling out the opening of the bottle, prevents the admission of liquid to the india-rubber disk, which, though it closes hermetically the bottle, is isolated from the liquid in a very simple manner.

We are aware that prior to our invention closing devices for bottles have been made. We therefore do not claim such a device broadly; but

What we do claim as our invention, and desire to secure by Letters Patent, is--

The combination in a bottle-closing device, of a collar-ring consisting of two halves of rectangular section that are linked or hinged at one end so as to be moved in a vertical direction, one of said halves being provided with a pin, the other with a hook which engages the pin in order to join both halves together, lever *d*, bar *i*, stopper *h*, rod *f* provided with a hooked end and link *k* substantially as described.

OTTO WUPPER

ALBERT BECKER.
